UNITED STATES PATENT OFFICE.

FREDERICK E. CARLSON, OF NEW BRITAIN, CONNECTICUT, ASSIGNOR TO LANDERS, FRARY & CLARK, OF NEW BRITAIN, CONNECTICUT, A CORPORATION OF CONNECTICUT.

ELECTRICAL COOKING DEVICE.

1,137,050.

Specification of Letters Patent. Patented Apr. 27, 1915.

Application filed August 7, 1913. Serial No. 783,475.

To all whom it may concern:

Be it known that I, FREDERICK E. CARLSON, a citizen of the United States, and a resident of New Britain, in the county of 5 Hartford, State of Connecticut, have invented certain new and useful Improvements in Electrical Cooking Devices, of which the following is a specification.

The invention relates particularly to an 10 electrical oven, and is concerned with the general mechanical construction of the body of the oven, with the construction of the electrical heater, and the manner of connecting it into circuit, and with additional features of construction which will be more 15 particularly pointed out in the following specification.

In the drawings—Figure 1 is a front view of an oven embodying my invention, Fig. 2 20 is a sectional view on the line 2—2 of Fig. 1, Fig. 3 is a plan view of the electrical heater with part of the cover plate broken away, Fig. 4 is a perspective view of the oven with a part of one side wall broken 25 away, Fig. 5 is a detail view of the door construction, Fig. 6 is a sectional view on the line 6—6 of Fig. 5.

Referring first to the mechanical construction of the oven, the main body of the oven, 30 comprising the sides *a*, *b*, and the back, *c*, is a double-walled structure formed from a single sheet of thin stock of proper width, which is folded about a form to the proper shape, the ends of the strip being united by 35 an interlocking seam as at *d*. Sheets of asbestos *e* are laid against the inner faces of these walls, and then spacers *f* are inserted to prevent collapse. The top and bottom are formed by fitting within the walls 40 of the body dished plates *g*, *h*, having at their side and rear edges lateral flanges *g'*, *h'*, arranged in a plane slightly below the top of the body, constituting pockets *g²*, *h²*, within which the top and bottom edges of 45 the inner wall of the body fit, the edges of the flanges abutting against the outer wall of the body. The ends of the sides *a*, *b*, and the fronts of the dished plates *g*, *h*, form the door opening in the front of the oven. 50 These dished plates are lined with sheet asbestos, and then receive spacers *f'* and are inclosed by cover plates *i*, *k*, the edges of which are bent down as indicated at *i'*, *k'* to cover over the joints between the body

and the top and bottom. Corner plates *l* 55 finish the top, and the feet *m* are located at the corners of the bottom. Tie rods *n* pass through the cover plate *i*, the dished plates *g*, *h*, the cover plate *k*, and the feet *m*, and have nuts threaded to their lower 60 ends, by means of which the parts of the oven are bound together. These tie rods constitute the only fastening, and by removing them the oven can be completely disassembled. The inner oven walls are free 65 from any kind of a fastening device, and joints are lapped so that no rough edges are left exposed, making it possible to thoroughly cleanse the inside of the oven when occasion demands. The door comprises a 70 frame *r* hinged to the end of one of the sides, *b*; the frame comprises a deeply channeled member *s* of rectangular form, having edge flanges, about which the edges of a finished plate *s'* are folded, forming a ledge 75 about the inner margin of the frame, on which the panel *t* of some transparent material, as glass, may be supported, held in place by the angle strips *u* which are secured by the clips *v* which engage the adjacent 80 ends of two of the angle strips. It is desirable to hold the panel securely in place, and the clips engage the angle strips rather than the material of the panel and so avoid damaging it. The door members of the 85 hinges are formed integrally with the door structure by rolling over the knuckles *s²* from the edge of the channeled member *s*. The door construction is of sheet metal and is very stiff, preventing sagging or warping, 90 and the knuckles formed integrally with the frame make a very rigid hinge support. The pivoted door latch *w* has a slotted end which engages a headed pin *w'* secured in the end of the side wall *a*, and the slotted end is 95 twisted slightly to have a camming action on the pin to cause the door to be tightly shut and its flanges to lie closely against the edges of the door opening to prevent the escape of heat from the interior of the oven. 100

The structure thus far described has been made the subject of a divisional application.

An important and desirable feature of this invention resides in the provision of a receptor 1 which has a sliding fit in the 105 oven, the base 2 of this receptor having upstanding side flanges 3 which will catch and retain drippings from anything which is be-

ing cooked. The side walls 4, 4, have ribs 5, upon which the heater may be slid in and out as well as the racks upon which is supported the food which is to be cooked. Thus it will be seen that the receptor not only supports the removable parts but also largely prevents the interior of the oven from becoming fouled, and may itself be removed for cleansing.

10. Mounted in the inner wall of the back are the sockets 7 at which the electrical connection of the heater is made. When the receptor is in the oven and the heater is to be used under the food, it slides in on the lowest pair of ribs, and as it is pushed into position the plugs 8 enter the lower socket and make electrical connection therewith. When the heater is to be used above the food, as in broiling, it slides in on the upper pair of ribs and makes electrical connections with the upper socket. The heater is preferably so wired as to produce three different heats, and the sockets are connected up with a 3-way switch 20, mounted on a bracket 21, and by means of which the circuit connections are established. A cover plate 22 having a slip connection with the bracket as at 23 is held in place by the screw 24 and conceals the wire connection of the sockets and attachment plug with the switch.

The heater is of rectangular shape and of a size to slide on the ribs in the receptor. As shown, it is composed of a wire frame 30 about which are wound the edges 31 of lateral flanges 32 extending from the sides of a shallow recessed base 33. 34 is a recessed cover plate slightly larger than the base plate 33 and secured thereto in any convenient manner. This plate is imperforate in order that when the heater is used under the food which is being cooked, any drippings or droppings will strike the cover plate and run off onto the flanges 32 of the base plate, where it can drip down through the apertures 35 to the bottom of the receptor. This protects the interior of the heater from the accumulation of dirt, grease, etc., and avoids the possibility of short-circuiting the resistance coil. When the heater is to be used above the food which is to be cooked, as in the case of broiling, it is turned up side down, and in place of the cover plate a wire netting is used, the base of the heater throwing the heat down onto the food.

Arranged around the edges of the recess in the base are metal strips 40 folded over a packing of electrical insulation 41, and the tops of these strips are transversely slotted at intervals as indicated at 42. Alternately short and long arms 43, 44, have their ends embedded in this insulating material where it is exposed by the slots, and have loops at their edges which support the resistance coils 45, 46. These coils are

stretched slightly as they are seated in the loops and then the loops are pinched to hold them under tension.

Centrally arranged within the heater is an annular band 50 which acts as a spacer between the top and bottom of the heater, and also as a diffuser of the heat, and the top and bottom plates are slightly recessed so as to position it. These depressions in the base and cover of the heater, as well as the offset in the base of the receptor, are also useful in determining the direction of movement of these plates as they expand when heated, and prevent the snapping and consequent jarring of the oven which would otherwise be occasioned if the plates were flat and free to buckle in either direction. This constitutes an important feature in the construction of the oven since the jarring of the structure which would otherwise be occasioned by the buckling and snapping of the plates interferes with the successful cooking or baking of various foods.

In the bottom of the heater apertures 51 are formed to permit of the circulation of air through and around the resistance coils. In the bottom plate 33 and near the back of the oven, small apertures 52 are formed, which provide an outlet for the air in the bottom of the oven as it expands, furnishing a supply of heated air to the interior of the oven and facilitating its operation. One end of the coil 45 is connected with the plug *x*; the corresponding end of the coil 46 is connected with the plug *y*; and the opposite ends of both coils are connected with the plug *z*. The connection of these plugs, *x*, *y*, *z*, is controlled through the 3-way switch 20, and the three heats are obtained first by connecting the coils in series, next by cutting out the coil 45, and next by connecting the coils up in parallel.

52 indicates a rack which may be of any desired construction suitable to slide in the receptor and support food which is to be cooked.

By this invention an oven of extreme simplicity in and economy of construction is provided, well insulated to conserve the heat, and well protected to insure its cleanliness. Novel means are provided for connecting up the heater with the circuit, and the heater itself is thoroughly protected against damage. The complete structure constitutes a very efficient and serviceable oven, requiring a minimum amount of current in the production of quick results.

Patent No. 1,129,381, S. No. 827,099, filed March 25, 1914, is a division of the present application.

I claim as my invention:—

1. In an electric oven, supporting ribs at opposite sides, an electrical heater adapted to move longitudinally on said ribs for positioning within the oven, contact plugs later-

ally projecting from one edge of the heater, and sockets mounted in the back of the oven below the wall and open to the interior thereof, said plugs and sockets adapted to be alternately engaged and disengaged by the horizontal movement of said heater into and out of position within the oven.

2. In an electric oven, sockets mounted in the back thereof below the plane of the inner wall of the back, in alignment with apertures therein, a receptor snugly fitting within and removable from said oven, side walls on said receptor provided with supporting ribs, an electrical heater slidable on said ribs into and out of said oven, and plugs projecting laterally from the rear edge of said heater and adapted to be alternately engaged with and disengaged from said sockets by the movement of the heater into and out of said oven.

3. The combination with an electric oven provided at its sides with oppositely projecting supporting ribs arranged in aligned pairs at different elevations, of an electric heater comprising a recessed base, lateral flanges, the edges of which are adapted to rest and slide upon said supporting ribs, an electrical resistance located within the recessed base, a cover plate overlying said recessed base and supported on said lateral flanges, said flanges being apertured beyond the edges of the cover plate.

4. A heater adapted for use in electric ovens and similar devices, comprising a shallow recessed base adapted to be supported at its side edges on the sides of the oven, strips of insulating material arranged about the sides of the recessed base, arms embedded in said insulating material with their ends bent to form inwardly extending lateral supports, and an electrical resistance coil arranged about the sides of said base and secured to said lateral supports.

5. A heater for use in electric ovens and similar devices comprising a shallow recessed base, an oppositely recessed cover plate secured thereto, an electrical resistance located around the sides of said base, and an annular ring arranged centrally of and extending between said base and cover.

6. A heater for use in electric ovens and like devices comprising a base, strips of electrical insulating material arranged about the sides of said base, arms embedded in said insulating material and having their ends bent to form inwardly projecting supports, some of which are of greater length than others, a pair of electrical resistance coils, one of which is mounted on the longer supports and the other on the shorter supports, a cover plate for said base, and an annular ring located within the inner coil and contacting at its edges with the base and cover plate.

7. A heater for use in electric ovens and similar devices, comprising a shallow recessed base, an oppositely recessed cover plate secured thereto, and an electrical resistance located within the base, said base and cover plate being centrally offset for the purposes set forth.

8. An electrical oven comprising a hollow-walled body and a door closure therefor, an electrical heater located within said body, circuit connections therefor, and a communicating passage between the interior of said body and one of its hollow walls.

9. An electrical oven comprising a hollow-walled body and a door closure therefor, an electrical heater removably located within said body, interengaging contact members on said body and heater.
